UNITED STATES PATENT OFFICE.

CHARLES M. CASHIN, OF BOSTON, MASSACHUSETTS.

DOOR-CHECK.

SPECIFICATION forming part of Letters Patent No. 372,655, dated November 8, 1887.

Application filed February 1, 1887. Serial No. 226,151. (No model.)

To all whom it may concern:

Be it known that I, CHARLES M. CASHIN, of Boston, in the county of Suffolk and State of Massachusetts, have invented an Improvement in Burglar-Proof Door-Checks, of which the following description, in connection with the accompanying drawings, is a specification, like letters on the drawings representing like parts.

10 This invention has for its object to provide a burglar-proof door-check which is especially adapted to be used by commercial men or drummers on the road.

15 My improved door-check is small in size and weight, and can be easily carried about the person from place to place without inconvenience. It is especially adapted for use in hotels and lodging-houses in the summer-time, when it is desired to effect a circulation of air through a 20 bed-room.

25 By means of my improved door-check the door of the room may be opened to any desired width, which in most cases will be sufficient to admit a considerable quantity of air, and yet not large enough to admit the body of a burglar.

The particular features in which my invention consists will be pointed out in the claim at the end of this specification.

30 Figure 1 is a side elevation of my improved burglar-proof door-check; Fig. 2, a section of Fig. 1 on line xx , and Fig. 3 a section of Fig. 1 on line xx with the pad omitted.

35 The base or body portion a will, for the best results, be of metal, cast to leave a beveled or inclined upper face, a' , and an oppositely-inclined rear face, a'' , the latter face having teeth or prongs b projecting beyond the bottom line of the body a .

40 The base or body portion a is cast so as to leave a hollow or depression in the inclined upper face, a' , having a bottom, b' , substantially parallel to the said upper face, the opposite ends of the said hollow or depression having, as herein shown, an opening, b' , for a purpose to be described.

45 The hollow or depression in the inclined up-

per face receives within it a pad, c , preferably of rubber, which for the best results is molded, it having at each end a tongue, c' , adapted to 50 be inserted through the opening b' in the ends of the said hollow depression, to more securely keep the rubber pad in place. The rubber pad c will also preferably be beveled, as shown.

55 In the application of my improved door-check it will be placed upon the floor away from the door the distance it is desired to open the latter, the bottom of the door passing up the inclined face, when the door is opened, until it comes in contact with the rubber pad. 60 If the door is pressed upon from the outside to open it still wider, the pressure exerted upon the said door will force the teeth or prongs into the floor, thereby offering a resistance to the pressure upon the door. The greater the 65 pressure upon the door the firmer the teeth b are driven into the floor, and consequently greater resistance is offered to the opening of the door.

70 My improved door-check may also be kept permanently in the room, and, if desired, it may be fastened by a chain (not shown) to the wall near the door.

75 It will thus be seen that the door may be left ajar to admit air into the room, which is especially advantageous in summer-time without any danger or fear of being burglarized.

I claim—

80 A burglar-proof door-check comprising the one-piece cast-metal base or body portion a , having the inclined face a' , provided with a hollow or depression, and the oppositely-inclined face a'' , having teeth b , combined with an elastic pad fitted into the hollow or depression in the face a' , as and for the purpose 85 specified.

In testimony whereof I have signed my name to this specification in the presence of two subscribing witnesses.

CHARLES M. CASHIN.
